UNITED STATES PATENT OFFICE

100,570

DESIGN FOR A BUTTER DISH

Albert Lowenfels, White Plains, N. Y.

Application May 4, 1936, Serial No. 62,468

Term of patent 14 years

To all whom it may concern:

Be it known that I, Albert Lowenfels, a citizen of the United States, residing at White Plains, in the county of Westchester and State of New York, have invented a new, original, and ornamental Design for Butter Dishes, of which the following is a specification, reference being had to the accompanying drawing, forming part hereof.

Fig. 1 is a perspective view of the butter dish, showing my design.

Fig. 2 is a sectional view taken transversely through the butter dish.

Fig. 3 is a front elevation of the upper part or cover of the butter dish.

Fig. 4 is a front elevation of the lower part or bottom of the butter dish.

I claim:

The ornamental design for a butter dish, as shown.

ALBERT LOWENFELS.
